UNITED STATES PATENT OFFICE.

HARRY STILLSON HART AND OTTO W. MEISSNER, OF CHICAGO, ILLINOIS.

DUMP-CAR.

SPECIFICATION forming part of Letters Patent No. 739,864, dated September 29, 1903.

Application filed January 30, 1903. Serial No. 141,146. (No model.)

To all whom it may concern:

Be it known that we, HARRY STILLSON HART and OTTO W. MEISSNER, citizens of the United States, residing at Chicago, in the county of 5 Cook and State of Illinois, have invented certain new and useful Improvements in Dump-Cars, of which the following is a specification.

The invention relates to that class of cars which is provided with what is known in the 10 art as a "dumping-bottom portion," and particularly to cars which are provided with dumping-hopper portions to facilitate the carrying of the material and the dumping or discharge thereof, as will more fully herein- 15 after appear.

The principal object of the invention is to provide a simple, economical, and efficient 20 hopper-bottom dumping-car with means to facilitate the discharge of materials therein.

Further objects of the invention will appear 25 from an examination of the drawings and the following description and claims.

The invention consists, principally, in a 30 hopper-bottom dumping-car, in which there are combined a supporting-frame portion, a V-shaped hopper portion extending longitudinally of the car and with its apex arranged at or near the longitudinal center of the car and the bottom portions of which are pivotally 35 secured to the underframing of the car, so as to provide a maximum opening and facilitate the dumping of the materials substantially as hereinafter set forth.

The invention consists, further, in a hopper-bottom dumping-car provided with a 40 supporting-frame portion, a V-shaped hopper portion extending longitudinally of the car with its apex arranged at or near the longitudinal center thereof and the entire distance between the inner axles of the car-trucks, the inclined side portions of which are divided into upper and lower portions extending above and below the underpinning of the car, with the lower portions pivotally 45 secured to the underpinning, and means for closing both of such bottom portions by and during one and the same operation, substantially as hereinafter set forth.

The invention consists, further and finally, 50 in the features, combinations, and details

of construction hereinafter described and claimed.

In the accompanying drawings, Figure 1 is a side elevation, partly broken away, of one end of a car as it appears when constructed 55 in accordance with these improvements; Fig. 2, a plan view of the same; Fig. 3, a longitudinal sectional elevation taken on line 3 of Fig. 2 looking in the direction of the arrow; Fig. 4, a cross-sectional view taken on line 4 60 of Fig. 1 looking in the direction of the arrow; Figs. 5, 6, and 7, enlarged sectional details of parts more fully hereinafter described.

In the art to which this invention relates it is well known that dumping-bottom cars 65 have become a necessity with the large rail-ways of the country and that in the use of V-shaped hopper-bottom cars which are self-discharging, particularly those known as the "Rodger" type, it is desirable to have the 70 hopper so constructed and arranged that it may be used for discharging ballast between the tracks in the desired shape—viz., by the use of one swinging portion. It is also well known that when it is made in this way it 75 has objections, in that it cannot be used to advantage for the discharge of other materials, such as coal, for the reason that such material is apt to stick in the discharging-opening. It is therefore desirable to provide 80 this type of car with maximum openings and so arrange it that it may also be used as the older Rodger type with minimum openings to carry and discharge ballast, all of which will be understood and appreciated by those 85 skilled in the art. In constructing a car in accordance with these improvements we make a car-body the underpinning of which is provided with side sills *a*, intermediate sills *b*, and non-continuous centersills *c*. The underpinning has secured to it upright or vertical 90 side frame portions formed of stakes *d* and upper portions *e*, secured thereto. End boards or portions *f* are also provided and secured to the underpinning, so that all of such parts 95 not only assist in carrying the load, but in the stiffening of the structure to withstand the stress and strains incident to ordinary use.

To provide means by which the load may be carried, we provide a V-shaped dumping- 100

hopper portion extending longitudinally and with the apex thereof arranged below the underpinning and at or near the longitudinal center of the car. This hopper portion is 5 formed of inclined sides divided into two parts—upper fixed parts *g*, the lower portions of which are secured to the intermediate sills and the upper part to the side framing of the car, and lower swinging portions *h* and *i*, 10 which in turn have their upper ends pivotally secured in metallic brackets *o*, attached to the lower inner edges of the intermediate sills—so that when the parts are in their closed or operative position, as shown partic- 15 ularly in Fig. 4, they are arranged at substantially the same angle, though in broken or different planes.

From an examination of Fig. 4 it will be seen that both of the lower swinging portions 20 may be swung open, so as to provide a maximum opening between the intermediate sills, and thereby facilitate the discharge of coal or loose bulky freight. It oftentimes becomes necessary, however, to provide means by which 25 one of such doors may be held closed while the other is operated, so as to use the car as a Rodger ballast-car—that is, a car in which one lower portion is movable and the other immovable. For this we provide one lower portion with a 30 suitable eyebolt *j*, adapted to be engaged by a hooked rod *k*, having its hooked end so arranged as to engage the eyebolt, and thus hold the near swinging portion closed, while the further swinging portion *h* is adapted to 35 be opened and closed, as desired. It is of course desirable that some simple mechanism be used which will effectually permit both of such lower swinging portions to be opened and closed by and during the same operation. 40 To provide such mechanism, a single rock-shaft *l* is used and rotatably mounted in the framework of the car. To this rock-shaft is secured a plurality of chains *m*, which are also secured to the lower free edge of the farther 45 swinging portion of the hopper, as shown at *n*. The lower ends of the near swinging portion of the hopper are provided with idler-rolls *p*, one for each chain, each of which is mounted in and between the metal bars *q*, 50 which are tied together by means of the bolt *r*, the bolt acting as a guide to keep each chain in engagement with its particular idler-roll. By this arrangement it will be seen that when the chains are wound up both of such 55 swinging doors are closed during one and the same operation, and when the rock-shaft is free to rotate both of such doors may be opened during the same operation. Again, it will be seen that when the hooks *k* are in engagement with the eyebolts *j* on the near swinging portion of the hopper such portion will remain stationary while the other swinging portion is free to operate. The rock-shaft 60 may be provided with ratchet-and-pawl mechanism *t*, (shown to the right of Figs. 1 and 2,) which is shown, described, and claimed in

Patent No. 716,075, granted to Otto W. Meissner the 16th day of December, 1902, which controls the operation thereof and needs no further description here, in that it forms no 70 material part of the invention.

We claim—

1. In a hopper-bottom dumping-car of the class described, the combination of a supporting-framework comprising longitudinal sills, 75 a V-shaped hopper extending longitudinally of the car with its apex at or near the longitudinal center thereof, the lower side portions of which are pivoted to the sills of the car and extending below the same, and means for 80 holding such pivoted portions in operative position, substantially as described.

2. In a hopper-bottom dumping-car of the class described, the combination of a supporting-framework comprising longitudinal sills, 85 a V-shaped hopper portion extending longitudinally of the car with its apex arranged at or near the longitudinal center thereof, the lower side portions of which are swingingly arranged and pivotally secured to the 90 longitudinal sills of the car and extending below the same, means for closing such swinging portions, and means for holding one of such pivoted portions closed and permitting the other to be opened and closed as desired, 95 substantially as described.

3. In a hopper-bottom dumping-car of the class described, the combination of a supporting-framework comprising bottom sills, a V-shaped hopper portion extending longitudinally of the car with its apex at or near the longitudinal center thereof, the inclined side portions of which are divided into two portions—upper portions arranged above the underpinning and lower swinging portions arranged below such upper hopper portions, angular metallic brackets mounted upon the bottom sills of the car-framework to which such lower swinging portions are pivotally attached, and means for closing such swinging portions and holding them in operative position, substantially as described. 105

4. In a hopper-bottom dumping-car of the class described, the combination of a supporting-framework comprising bottom sills, a V-shaped hopper portion extending longitudinally of the car with its apex arranged at or near the longitudinal center thereof and its inclined side portions which form the hoppers divided into two parts—an upper fixed part 115 secured to the framework of the car and above the underpinning and lower swinging portions arranged below the underpinning, angular metallic brackets secured to the bottom sills of the framework and pivotally connected to such lower swinging portions, and means for closing and holding the swinging portions in operative position, substantially as described. 120

5. In a hopper-bottom dumping-car of the 130 class described, the combination of a supporting-framework comprising bottom sills, a V-

- shaped hopper portion extending longitudinally of the car with its apex at or near the longitudinal center thereof and below the supporting-framework of the car, the inclined 5 side portions of which are divided into fixed upper portions arranged above the underframing and rigidly secured to the car-frame and lower swinging sections pivotally secured to the bottom sills of the car and extending 10 below the same, a single rock-shaft, and chain mechanism secured to such rock-shaft and one of such swinging sections and contacting the other swinging portion for closing and holding such doors in operative position, substantially as described.
6. In a hopper-bottom dumping-car of the class described, the combination of a supporting-framework comprising bottom sills, a V-shaped hopper portion extending longitudinally of the car with its apex arranged at or near the longitudinal center thereof and below the underpinning of the car, the inclined side portions of which forming the hopper are divided into two sections—upper fixed 20 sections arranged above the underpinning and lower swinging sections arranged below and pivotally secured to the bottom sills, a single rock-shaft, chain mechanism secured to such rock-shaft and to the farther lower 25 swinging portion of the hopper and engaging with the other swinging portion of the hopper to close both of such doors by and during one operation of the rock-shaft, substantially as described.
- 30 7. In a hopper-bottom dumping-car of the class described, the combination of a supporting-framework, a V-shaped hopper portion extending longitudinally of the car with its apex arranged at or near the longitudinal center 35 thereof, the inclined sides of which form the hopper and are divided into two portions—an upper portion arranged above and fixedly secured to the underpinning and a lower swinging section arranged below the underpinning and pivotally secured thereto, a single rock-shaft, chain mechanism secured to such rock-shaft and to one lower swinging section of the hopper, and idler mechanism secured to the lower edge of the other swinging section of 40 the hopper and contacted by the chain, whereby both of such lower swinging sections are closed by and during the same operation of the rock-shaft, and means for holding one of the swinging sections closed and permitting 45 the other to be opened and closed as desired, substantially as described.
- 50 8. In a hopper-bottom dumping-car of the class described, the combination of a supporting-framework, a V-shaped hopper portion extending longitudinally of the car with its apex arranged at or near the longitudinal center thereof, the inclined side portions of which form the hopper and are divided into two parts—upper sections arranged above the underpinning and secured thereto and lower swinging sections pivotally secured to the un-
- derpinning below the same so as to provide a maximum-discharge opening when desired, rock-shaft and chain mechanism for closing both swinging sections by and during the same operation, and means for holding one swinging section closed and permitting the other to be opened and closed as desired, substantially as described.
9. In a hopper-bottom dumping-car of the class described, the combination of a supporting-framework, a V-shaped hopper portion extending longitudinally of the car with its apex arranged at or near the longitudinal center thereof, the inclined side portions of which 70 form the hopper and are divided into two parts—upper fixed sections arranged above the underpinning and secured thereto and lower swinging sections pivotally secured to the underpinning below the same so as to provide a maximum-discharge opening when desired, rock-shaft and chain mechanism for closing both doors by and during the same operation, and hook-and-staple mechanism for holding one of such doors closed and permitting the other to be opened and closed as desired, substantially as described.
10. In a hopper-bottom dumping-car of the class described, the combination of a supporting-frame having side and intermediate sills, 75 non-continuous center sills, a V-shaped hopper portion extending longitudinally of the car with its apex arranged at or near the longitudinal center thereof and the inclined side portions of which are divided into two sections—upper fixed sections arranged above the intermediate sills with their lower ends secured thereto and lower swinging sections with their upper ends pivotally secured to the lower portions of the intermediate sills, and 80 means for opening and closing the same, substantially as described.
11. In a car of the class described, the combination of a car-supporting frame having side and intermediate sills, a V-shaped hopper portion extending longitudinally of the car with its apex arranged at or near the longitudinal center thereof, the inclined side portions of which are divided into two sections—upper fixed sections fixedly secured to the 85 side of the car and to the intermediate sills and lower swinging sections pivotally secured at their upper ends to the lower parts of the intermediate sills so as to provide a maximum-discharge opening, a single rock-shaft, 90 chain mechanism secured to such rock-shaft and to the farther swinging section, idler-roll mechanism on the lower portion of the near swinging section and contacting the chain so that both of such doors may be closed by and 95 during the same operation, and means for holding the near swinging section closed while the farther swinging section may be independently opened and closed, substantially as described.
12. In a hopper-bottom dumping-car of the class described, the combination of a support-

ing-framework, a V-shaped hopper portion extending longitudinally of the car with its apex arranged below the underpinning and at or near the longitudinal center thereof and having inclined side portions, each of which is provided with lower swinging sections, means for operating such sections so as to close the same and permit them to be opened,

and means for holding one section closed while permitting the other to be operated as desired, substantially as described.
